UNITED STATES PATENT OFFICE.

JOHAN OTTO EMANUEL TROTZ, OF WORCESTER, MASSACHUSETTS.

APPARATUS FOR CASTING INGOTS IN CONTINUOUS LONG LENGTHS.

SPECIFICATION forming part of Letters Patent No. 705,721, dated July 29, 1902.

Application filed April 28, 1900. Serial No. 14,708. (No model.)

To all whom it may concern:

Be it known that I, JOHAN OTTO EMANUEL TROTZ, of the city and county of Worcester and State of Massachusetts, have invented 5 certain new and useful Improvements in Apparatus for Casting Ingots in Continuous Long Lengths; and I do hereby declare that the following is a full, clear, and exact description thereof, reference being had to the 10 accompanying drawings, forming a part of this specification, and in which—

Figure 1 represents a side view, partly in section, of so much of an apparatus for casting ingots in continuous long lengths as is necessary to illustrate my improvements, and Fig. 15 2, represents upon an enlarged scale, a vertical central section through the part of said apparatus to which said improvements relate.

The object of this invention is to cover cer- 20 tain improvements not embodied in my former application for United States Letters Patent for a similar apparatus, filed December 17, 1898, bearing Serial No. 699,525, allowed October 9, 1899, and which was issued April 24, 25 1900, as Patent No. 648,091.

To enable others skilled in the art to which my said invention appertains to better understand the nature and purpose thereof, I will now proceed to describe it more in detail.

30 In the drawings, A represents the outer case or jacket, which is provided with the hollow heads B and C, having the annular water-chambers B' C', respectively. Within said jacket and heads are centrally and longitudinally arranged the ingot-mold D, which fits in central openings in said heads and has an annular chamber E surrounding the same between it and the jacket A. Said jacket is fastened at or near its ends to the heads B C, in 35 this instance by providing a portion of the exterior of each end thereof with threads and securing said ends into threaded openings in the heads, as is shown in Fig. 2 of the drawings. Any other method of fastening, however, 40 may be adopted, if desired.

In order to obtain a free circulation between the chambers B' C' in heads B C and the annular chamber E around the ingot-mold, the jacket A is made a little shorter than the distance between the inside of the outer end walls of the heads, so as to leave an opening F at each end, as is also shown in Fig. 2. The

heads B C are also provided one with an inlet or supply-pipe G and the other with a discharge-pipe H, by means of which and the 55 aforesaid chambers a free and uniform circulation of water or other cooling medium may be maintained around the ingot-mold throughout its entire length between said outer end walls of the heads. 60

In practice the water is preferably admitted at the bottom through the supply-pipe G and after flowing up around the ingot-mold discharged at the top through the pipe H; but, if preferred, the direction of said flow of water 65 may be reversed. By thus maintaining a uniform flow of water or other cooling medium around the ingot-mold it is obvious that the molten metal passed through it may be cooled uniformly on all sides. 70

The essential features of my invention consist, as before stated, in constructing the apparatus so that the ingot-mold may freely expand longitudinally and in elongating the funnel I, into which the molten metal is 75 poured, so that it will extend a considerable distance into said ingot-mold and the molten metal. Said longitudinal expansion of the ingot-mold may be accomplished in various ways. I prefer in practice, however, to effect 80 said result by fitting the lower end of said ingot-mold loose in the bottom head C of jacket A, so that it may freely slide longitudinally therein to allow of said longitudinal expansion. The joint between the two parts 85 may be made practically water-tight, while also admitting of said longitudinal slide motion, by using a suitable elastic packing J, fastened in the head and bearing against the surface of the mold, as is shown in Fig. 2. 90

Either the top or bottom end of the ingot-mold may be constructed to slide in its respective head, as aforesaid, or, if preferred, both ends may be fastened rigid to the heads and the longitudinal expansion thereof obtained by constructing the jacket so that it may be elongated by said expansion of the ingot-mold. This may be done by making the jacket in two or more longitudinal sections, one overlapping the other, as is shown 100 at K in Fig. 2, with a tight close-fitting joint between said overlapping ends, adapted to prevent the water from escaping at said point and also admitting of longitudinal motion

one against the other to conform to the expansion of the ingot-mold. If desired, a packing L may be used to prevent said escape of water, said packing being held in place by 5 suitable means, as in the previously-described instance, for making the slide-joint at the end of the ingot-mold water-tight. This feature of allowing for the longitudinal expansion of said ingot-mold is an important one in practice, for the reason that if such expansion or elongation of the mold is not provided for it will be caused to bend laterally or "buckle" between the two fastened ends by the expansion produced in pouring the molten metal 15 therein, thereby preventing the metal from being readily drawn from the mold, and in consequence forming imperfect ingots. It is not only important that the ingot-mold be prevented from buckling, as aforesaid, but 20 also that the interior thereof shall be worked and polished to a perfectly straight and smooth surface, as described in my former application hereinbefore referred to, in order that the metal may readily pass down 25 and be easily drawn from said mold as fast as it is cooled at the bottom to the proper degree of hardness to sustain itself and retain its shape.

The process of cooling and continuously 30 drawing the metal from the mold is fully described in my said former application, and it will therefore be unnecessary to enter into a detailed description thereof in the present case.

35 In Fig. 1 of the drawings I have shown the metal as being drawn from the mold by means of a hydraulic piston M (only the upper end of which is shown) and a piston-rod N, whose head O serves as a support for the 40 metal until the bottom portion thereof has become sufficiently hardened to retain its shape, as aforesaid. Having become thus hardened by the cooling medium around the mold to the proper degree to be drawn forward, it is drawn down between the first two rolls P, which then feed it forward continuously as long as the metal is poured into the 45 mold.

The method of pouring the molten metal 50 from a funnel whose lower end comes a considerable distance above the mold is objectionable on account of spattering said metal onto the sides of the mold, to which it adheres and causes an uneven body of metal to 55 be formed at the top, liable to contain "blow-holes" and "pipes," and to obviate this objection what is known as "bottom" casting or pouring the molten metal in at the bottom, so that it will flow up and fill the mold, is 60 adopted.

I find that by elongating the funnel I so that its nozzle I' may extend down into the mold and molten metal, as is shown in Fig. 2, I am enabled to accomplish substantially the same re-

sult as by bottom casting and by a method 65 which is applicable to my improved process of forming the ingots and drawing them down from the mold continuously, as is fully described in my former application and partially described in the foregoing description. By 70 thus using a funnel extending down into the molten metal, which is poured in as fast as it is drawn from the bottom, I do away with all spattering, and the upper end of the metal bath is kept of as uniform texture as the rest of the 75 body of the metal which has been previously poured. While the construction employed in effecting this result is very simple, it is of the utmost importance in practice, inasmuch as I am thereby enabled to produce ingots of 80 uniform quality free from blow-holes and pipes. It will at once be apparent that by thus extending the nozzle of the funnel down into the body of the metal being poured it is impossible to cause any spattering thereof, 85 for the reason that sufficient metal is constantly supplied to maintain about the level shown in Fig. 2 and keep the nozzle buried beneath the surface of the molten metal.

Having now described my invention, what 90 I claim therein as new, and desire to secure by Letters Patent, is—

1. The combination of jacket A, and hollow heads B, C, the latter fastened to the ends of said jackets and having supply and 95 discharge pipes, also having separate openings to receive and hold the ends of the ingot-mold D, with said ingot-mold, the latter held rigid at the upper end in head B, fitted loose at its lower end in head C, and whose inner 100 surface is polished straight and smooth, and the funnel I, said funnel having the downward extension I' into the ingot-mold, and fastened to head B, substantially as and for the purpose set forth.

105 2. The jacket A and hollow heads B, C, the latter fastened to the ends of said jacket and having supply and discharge pipes, also having separate openings to receive and hold the ends of the ingot-mold D, the latter being held rigid in the upper end in head B, fitted loose at its lower end in head C, and whose inner 110 surface is polished straight and smooth, and the funnel I, said funnel having the downward extension I' into the ingot-mold, 115 and fastened to head B, in combination with means for supporting the molten metal in the ingot-mold until properly cooled to draw, for conducting it to the rolls of the rolling-mill, and said rolls; said means for supporting and 120 conducting the metal comprising the vertically-operating piston M, connecting-rod N and head O, substantially as and for the purpose set forth.

JOHAN OTTO EMANUEL TROTZ.
